UNITED STATES PATENT OFFICE.

JOHN V. ALLEN, OF SOUTH WEYMOUTH, AND EDWARD E. ORR, OF WEYMOUTH, MASSACHUSETTS, ASSIGNEES, BY MESNE ASSIGNMENTS, TO UNITED SHOE MACHINERY CORPORATION, OF PATERSON, NEW JERSEY, A CORPORATION OF NEW JERSEY.

SHOE-SEWING MACHINE.

1,286,869.

Specification of Letters Patent.

Patented Dec. 3, 1918.

Application filed January 10, 1916. Serial No. 71,307.

To all whom it may concern:

Be it known that we, JOHN V. ALLEN and EDWARD E. ORR, citizens of the the United States, residing at South Weymouth and 5 Weymouth, respectively, in the county of Norfolk and Commonwealth of Massachusetts, have invented certain new and useful Improvements in Shoe - Sewing Machines; and we hereby declare the following to be a full, clear, and exact description of the invention, such as will enable others skilled in the art to which it appertains to make and use the same.

This invention relates to shoe sewing machines, and more particularly to shoe sewing machines of the type having a curved hook needle and a work feeding awl, and employed in sewing outsoles to the welts of welted shoes.

20 In the manufacture of rubber soled welted shoes, outsoles having block heels formed integral therewith are used to a considerable extent by manufacturers. A rubber outsole is sewed to the welt of the shoe in substantially the same manner as the outsole of an all leather shoe, except that a longer stitch is ordinarily employed. In the operation of stitching a rubber outsole having an attached heel to the welt, the first stitch is, of course, placed as close as possible to the breast line of the heel. The outsole stitchers at present in common commercial use comprise a curved hook needle and a work feeding awl which during each cycle of operations after piercing the work at a point to the rear of the needle in the direction of feed, moves laterally to a limiting position in line with the needle to feed the work. The needle then follows the awl through the work as the awl retracts from the work. The work is inserted in the machine with the parts in the positions which they assume at the point in a cycle of operations where both the needle and awl are retracted out of work-engaging position. This occurs when the awl is in its limiting rearward position in the line of feed ready to pierce and feed the work. When a rubber outsole having an integral or attached heel is sewed to the welt of the shoe on such a machine as heretofore constructed, the sole is inserted between the work support and presser foot in position with the breast of the heel resting close up against the left end

or side of the presser foot. When the machine is started the awl pierces the work and feeds the same the distance of a normal stitch length before the needle pierces the work. In placing the shoe in the machine the shoe cannot be positioned so that the breast of the heel lies in the plane of the needle, since the presser foot extends to the left somewhat beyond this plane. The result is that the first stitch is formed more than the normal stitch length from the breast line of the heel, and the appearance of the stitching is greatly impaired. The presser foot of the type heretofore employed on these machines extends some distance to the rear of the sewing point, and as the seam is being completed the heel strikes the presser foot and thus prevents the last stitch from being formed close to the breast of the heel.

The primary object of the present invention is to provide an attachment for outsole shoe sewing machines for use in sewing rubber or other outsoles having a heel attached to enable the first and last stitches of the seam to be formed close to the breast of the heel.

With the above object in view, the invention comprises the improved and novel features hereinafter described and pointed out in the claims, the advantages of which will be obvious to those skilled in the art.

The invention will be readily understood from an inspection of the accompanying drawings illustrating the invention in its preferred form, and the following detailed description.

In the drawings, Figure 1 is a view in side elevation of an outsole shoe sewing machine to which the invention is applied;

Fig. 2 is a detail plan view partly in section illustrating particularly the feeding mechanism of the machine;

Fig. 3 is a detail view in side elevation partly in section of the mechanism shown in Fig. 2;

Fig. 4 is a detail view in front elevation illustrating the construction of the presser foot;

Fig. 5 is a diagrammatic view illustrating the needle and the parts of the feed mechanism in the position which they normally occupy at the time when both the needle and awl are in retracted position;

Fig. 6 is a view similar to Fig. 5 illustrating the parts in the position which they occupy when both the needle and awl are in retracted positions and the mechanism for imparting feeding movements to the awl has been adjusted to render the same inoperative, before the machine is started; and

Fig. 7 is a view similar to Fig. 5 illustrating the parts in the positions which they assume in the first cycle of operations just before the needle pierces the work.

The sewing machine illustrated in the drawings is a wax thread, curved hook needle, lock stitch machine for sewing out soles to the welts of welted shoes, and except as hereinafter described, has substantially the same construction, arrangement and mode of operation of parts as the machine illustrated and described in the application of Fred Ashworth, Serial No. 585,116, filed October 3, 1910, upon which Patent No. 1,169,909, dated February 1, 1916, was granted. This machine comprises a curved hook needle 2, a loop taker 4, a work feeding awl 6, a work support 8, and a presser foot 10. During each cycle of stitch-forming operations of the machine, starting just after the loop has been pulled from the loop taker and drawn down into the work to complete the stitch, the awl pierces the work and then moves laterally into line with the needle to feed the work. The awl then retracts from the work followed closely by the needle which is projected through the work into position to receive the thread from the looping device. After the needle retracts from the work holding a loop of thread in its hook, the loop is lifted by the thread lifter into the range of action of the hook of the loop taker. The loop is then carried over the loop taker, and is pulled from the loop taker and drawn down into the work by the action of the takeup.

The needle 2 is secured to a needle carrier 14 mounted to turn co-axially with the awl. The needle carrier is oscillated to actuate the needle as above described through connections from a continuously rotating crank. These connections comprise a bell crank lever 16, a link 18 connecting one arm of the bell crank with the needle carrier, and a link 20 connecting the other arm of the bell crank with the crank 22 carried by the continuously rotating shaft 24.

The awl 6 is mounted on the awl carrier 26 which is secured to a rod or pin 28 which forms a pivot for the carrier. This rod is mounted so as to be capable of oscillating and longitudinal movements in two stationary arms 30 projecting forwardly from the frame of the machine. The awl carrier is oscillated to impart oscillating movements to the awl by means of an awl driver 32 mounted to oscillate co-axially with the awl carrier, the awl carrier having a sliding

driving engagement with the awl driver. The mechanism for actuating the awl driver to oscillate the awl carrier and awl in timed relation to the needle as hereinbefore described comprises a bell crank lever 36, a link 40 connecting one arm of the bell crank with the awl driver, a lever 42, a link 44 connecting the other arm of the bell crank 36 with the forward end of the lever 42, a continuously rotating crank 46, and a link 48 connecting the rear end of the lever 42 with the crank.

The pin 28 is moved back and forth longitudinally to impart lateral feeding and return movements to the awl and awl carrier by means of two pivoted levers 52 and 54 arranged substantially parallel to each other, the forward ends of which engage slots in bearing pins or buttons 56 provided with conical ends engaging conical recesses in the ends of the pin. The lever 52 is cam actuated, and the two levers are connected by a link 58 so that the levers are actuated in unison, and the movements of the pin 28 in both directions are produced by the movements of the levers. The lever 52 is extended rearwardly beyond its pivot, and is pivotally connected to one member 60 of a toggle lever comprising the two pivotally connected members 60 and 62. The middle joint 64 of the toggle lever is connected by a link 66 to one arm of a bell crank cam lever 68, the other arm of which is provided with a roll 70 engaging a cam groove 72 in a cam disk 74 attached to the main shaft 76 of the machine. The movements of this bell crank lever impart through the connections above described positive movements in both directions to the levers 52 and 54, and to the pin 28 upon which the awl carrier is mounted. To enable the extent of the longitudinal movements of the pin 28 to be varied, as may be desired to produce the required length of stitch, the member 62 of the toggle lever is pivotally connected at 76 to a yoke 78 which is pivotally mounted above and below the toggle lever to turn on an axis 80 as is best shown in Fig. 2. By swinging the yoke about its pivot, the position of the toggle lever is changed so that when the toggle is actuated by the bell crank 68, more or less movement is imparted to the lever 52, and consequently to the pin 28 of the awl carrier. The pivot of the yoke 78 is arranged to be in line with the pivotal connection 64 between the members 60 and 62 of the toggle lever when said lever is in its extreme rearward position, which is the position which the toggle lever assumes after the awl has been moved to the left and is at the limit of its feeding movement. An adjustment of the yoke 78 about its pivot to vary the length of feed does not, therefore, vary the position of the awl at the end of its feeding movement, so

that with all lengths of feed the awl is always moved to the same point directly in line with the needle. To enable the length of feed to be readily adjusted by the operator to give the desired number of stitches to the inch either on different shoes or on different parts of the same shoe, the yoke 78 is provided with an arm 82 connected by a link 84 to one arm of a bell crank lever 86, the other arm of which is connected by a link 88 to a hand-operated lever 90 which is arranged in convenient position to be moved by the operator. The hand lever 90 extends over a perforated gage plate 92 attached to the frame of the machine in the holes in which pins may be inserted on each side of the lever 90 to limit movement of the lever in either direction.

The mechanism for oscillating the needle and awl and the mechanism for imparting feed movements to the awl have substantially the same construction and mode of operation as the corresponding mechanisms illustrated in the Ashworth application referred to above.

To permit the shoe to be inserted in operating position in the machine, or to permit the shoe to be removed from the machine when a seam has been completed, it is essential that the parts of the machine be placed in the positions which they assume at a point in a cycle of operation when the needle and awl are both retracted or disengaged from the work. As hereinbefore stated, in machines of this type the needle follows the awl through the work as the awl retracts from the work and the needle reaches a retracted position only after the awl has moved back from its position in line with the needle to its starting position in the line of feed. The needle and awl are, therefore, both in retracted positions only when the awl is a stitch length to the rear of the needle in the direction of feed. Fig. 5 shows diagrammatically the normal relative positions of the awl and needle in the line of feed, and also the normal positions of the other parts of the feed mechanism at the time when the needle and awl are both retracted from the work or when they occupy positions suitable for permitting the insertion or removal of work. When the work is inserted with the needle and awl and the parts of the feed mechanism in the positions shown in this figure, and the machine is then started, the awl pierces the work and feeds the work a normal stitch length before the needle penetrates the work. In sewing a rubber sole having an integral block heel or a sole having an attached heel to the welt of the shoe, the sole and welt of the shoe are inserted between the work support and presser foot, and the shoe is positioned so that the breast of the heel rests against the left end of the presser foot,

which, for this kind of work, is preferably made somewhat shorter than that usually employed to enable the breast of the heel to lie close to the plane of the needle. To prevent the awl from feeding the work a distance equal to the length of one stitch before the needle pierces the work and thereby locating the first stitch a feed length from the breast of the heel, the feed mechanism is adjusted before the machine is started to place the awl in line with the needle and to render the feed mechanism inoperative until after the needle has pierced the work in the first cycle of operations, and mechanism is provided which acts automatically to restore the feed mechanism to its normal operation after the needle has penetrated the work. In the construction illustrated the lever 90 is held in forward or normal position by mechanism comprising a yoke 94 pivotally connected by a pin 96 with the hand lever 90, and a rod 98 engaging at its forward end in spaced bearings in the yoke 94 and having its down-turned rear end engaged in an opening in the frame. The forward or normal position of the lever 90 is determined by an adjustable stop collar 100 mounted on the forward end of the rod 98 against which the yoke 94 is held by a coiled spring 102 surrounding the rod and interposed between the yoke 94 and a collar 104 on the rod. With this construction the length of feed is varied by adjusting the stop collar 100 longitudinally of the rod 98.

As has been explained above, the cam lever 68 in actuating the toggle lever 60-62 to cause the awl to feed the work always moves the pivotal connection 64 at the central joint of the toggle into line with the pivot of the yoke 78 regardless of the position of the yoke. With the parts in the position shown in Fig. 5 before starting the machine the operator seizes the lever 90 and swings this lever to the rear until its movement is limited by its engagement with a stop pin 95 placed in the perforated gage plate 92 to the rear of the lever. This movement of the hand lever turns the bell crank 86 and the yoke 78 and swings the pivotal connection between the member 62 of the toggle lever and the yoke about the axis of the yoke. The stop 95 is located so that when the movement of the hand lever is arrested by the stop the swinging movement of the yoke 78 has brought the pivotal connection between the member 62 of the toggle lever and the yoke to a position such that the line connecting the center of this pivotal connection with the center of the pivotal connection between the member 60 of the toggle and the lever 52 lies midway between the center of the central joint of the toggle and the axis of the yoke 82, as shown in Fig. 6. This brings the awl into line with the needle as will be readily seen 130

4
by an inspection of Fig. 6. With the parts of the feeding mechanism in the relative positions shown in this figure, upon starting the machine the awl will remain substantially stationary in the line of feed during the movement of the cam lever 68 which in the normal operation of the feeding mechanism produces the lateral feeding movement of the awl. As the machine is started 10 the awl pierces the work and the cam lever 68 is then moved from the position shown in Fig. 6 to that shown in Fig. 7, this movement of the cam lever in the normal operation of the machine imparting the feed 15 movement to the awl. This movement of the cam lever moves the central joint 64 of the toggle lever from the position shown in Fig. 6 to a position in line with the axis of the yoke 78 as shown in Fig. 7. The 20 movement of the cam lever, therefore, imparts substantially no movement to the awl, and the awl is still in line with the needle when the needle pierces the work.

In order to hold the hand lever 90 in the 25 position illustrated in Figs. 6 and 7 until the needle has pierced the work in the first cycle of operations, the catch 106 is secured to the hand lever, and as the lever is swung to the rear into engagement with the stop pin 95, this catch engages the rear end of the catch 30 plate 108 secured to the frame of the machine. The engagement of the catch 106 with the catch plate 108 holds the lever 90 in its rearward position until after the machine 35 is started.

As soon as the needle has pierced the work in the first cycle of operations, the hand lever 90 is automatically released and moved forward to normal position, thereby restoring the parts of the feed mechanism to their 40 normal operation. To this end a release plate 110 is secured to the forward end of one arm of the lever 112 which actuates the auxiliary take-up. The forward end of this 45 arm is lifted during each cycle of operations of the machine just after the needle has pierced the work. The inturned lower end of the release plate 110 carries an abutment screw 114 which is in position to engage the underside of the rear end of the catch 106 50 when this catch is engaged with the catch plate 108. Just after the needle has pierced the work in the first cycle of operations the forward end of the arm of the lever 112 to 55 which the plate 110 is secured is lifted thereby lifting the plate and engaging the abutment screw 114 with the underside of the catch 106 to release the catch from the catch plate 108. Upon the release of the catch 60 plate 108 the lever 90 is swung forward by the action of the spring 102 until the yoke 94 engages with the stop collar 100, thereby restoring parts of the feeding mechanism to their normal positions so that the 65 normal feeding operation of this mechanism

is resumed and continued during the remainder of the sewing operation.

As will be noted from an inspection of Fig. 4, the presser foot of the machine illustrated is formed with a shank 116 having a substantially vertical face 118 extending upwardly in the vertical plane of the rear edge of the presser foot for a distance at least equal to the thickness of the heel of the shoe. With this construction, in finishing the seam, the heel of the shoe will not strike the shank of the presser foot until the breast of the heel 75 engages the forward edge of the foot, and the seam may be formed close up to the breast of the heel. 80

Having explained the nature and object of the invention, and having specifically described a machine embodying the invention in its proper form, what is claimed is:—

1. A shoe sewing machine, having, in combination, a needle, a work feeding awl moving during each cycle of operation into a position in line with the needle to feed the work, mechanism for imparting feed movements to the awl, means for rendering said mechanism inoperative until after the needle has pierced the work in the first cycle of operations, and means acting automatically to restore said mechanism to its normal operation. 95

2. A shoe sewing machine, having, in combination, a needle, a work feeding awl moving during each cycle of operations of the machine into a position in line with the needle to feed the work, mechanism for imparting feed movements to the awl, means for placing the awl in line with the needle and for rendering said mechanism inoperative until after the needle has pierced the work in the first cycle of operation, and means acting automatically to restore said mechanism to its normal operation. 100

3. A shoe sewing machine, having, in combination, a work feeding awl, a needle arranged to follow the awl through the work, mechanism for moving the awl into a position in line with the needle during each cycle of operations to feed the work, means for rendering said mechanism inoperative until after the needle has pierced the work in the first 115 cycle of operations, and means acting automatically to restore said mechanism to its normal operation.

4. A shoe sewing machine, having, in combination, a needle, a work feeding awl, mechanism for moving the awl into a position in line with the needle during each cycle of operations to feed the work, means for rendering said mechanism inoperative until after the needle has pierced the work in the first 120 cycle of operations, and machine controlled means for restoring said mechanism to its normal operation. 125

5. A shoe sewing machine, having, in combination, a needle, a work feeding awl, 130

- mechanism for actuating the awl to feed the work, means for interrupting the feeding operation of the awl until after the needle has pierced the work in the first cycle of 5 operations, and means acting automatically to restore the awl to its normal operation.
6. A shoe sewing machine, having, in combination, a needle, a work feeding device, mechanism for actuating the work feeding 10 device normally to feed the work during each cycle of operations, means for interrupting the feeding operation of the work feeding device until after the needle has pierced the work in the first cycle of operations, and automatically controlled and operated means for restoring said device to its 15 normal operation.
7. A shoe sewing machine, having, in combination, stitch forming devices including a 20 needle, a work feeding device, mechanism for imparting feed and return movements to the work feeding device comprising a toggle lever, a connection between one member of the toggle lever and the work feeding 25 device, a pivoted support for the other member of the toggle lever, means for actuating the toggle lever, means for adjusting the support about its pivot to render said mechanism inoperative until after the needle has 30 penetrated the work in the first cycle of operations, and means acting automatically to restore said support to its normal position.
8. A shoe sewing machine, having, in combination, stitch forming devices including a 35 needle, a work feeding device, mechanism for imparting feed and return movements to the work feeding device comprising a toggle lever, connections between one member of the toggle lever and the work feeding 40 device, a support for the other member of the toggle lever, means for actuating the toggle lever, means for moving the support about an axis passing through the center joint of the toggle when the feeding device 45 is at the limit of its return movement to render said mechanism inoperative until after the needle has penetrated the work in the first cycle of operations, and means acting automatically to restore said support to 50 its normal position.
9. A shoe sewing machine, having, in combination, stitch forming devices including a needle, a work feeding device, mechanism for imparting feed and return movements to 55 the work feeding device, comprising a toggle lever, connections between one member of the toggle lever and the work feeding
- device, a support for the other member of the toggle lever, a cam actuated lever, a link connecting said lever to the central joint of 60 the toggle, a hand lever and intermediate connections for adjusting the support to render said mechanism inoperative until after the needle has penetrated the work in the first cycle of operations, and mechanism 65 acting automatically to restore said support to its normal position.
10. A shoe sewing machine, having, in combination, a needle, a work feeding device, mechanism for actuating the work 70 feeding device normally to feed the work during each cycle of operations, means for adjusting said mechanism to render the same inoperative until after the needle has pierced the work in the first cycle of operations, and machine controlled means for restoring said mechanism to its normal operation. 75
11. A shoe sewing machine, having, in combination, a needle, a work feeding device, mechanism for actuating the work feeding device normally to feed the work during each cycle of operations, means for rendering said mechanism inoperative until after the needle has pierced the work in the first 80 cycle of operations, and means including a timing device for restoring said mechanism to its normal operation after the needle has pierced the work. 85
12. A shoe sewing machine, having, in combination, a needle, a work feeding device, mechanism for actuating the work feeding device to feed the work, means for adjusting said mechanism to render the same inoperative until after the needle has 90 pierced the work in the first cycle of operations, a catch for holding said mechanism in an inoperative condition, and machine operated means for releasing the catch after the needle has pierced the work. 95
13. A sewing machine, having, in combination, stitch forming devices including a needle, a work feeding device, mechanism for actuating the work feeding device normally to feed the work during each cycle 100 of operations, means for rendering the work feeding device inoperative to feed the work at the beginning of the sewing of a seam, and automatically controlled and operated mechanism for restoring the work feeding 110 device to its normal operation during the first part of the seam formation.

JOHN V. ALLEN.
EDWARD E. ORR.
